UNITED STATES PATENT OFFICE

WILLIAM B. TUCKER, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE

TURBINE BLADE MOUNTING

Application filed April 5, 1930. Serial No. 441,821.

The present invention relates in general to improvements in the art of mounting a plurality of elements upon a support, and relates more specifically to an improved method of and apparatus for rigidly but detachably fastening a group of blades to a supporting rotor or casing.

An object of the invention is to provide an improved method of firmly attaching a group of blades or the like to a support such as a rotor, in such a manner that the blades may be readily removed without damaging the support. Another object of the invention is to provide simple and effective instrumentalities for enabling commercial exploitation of the improved method.

It is necessary in the construction of high speed rotary machines such as steam turbines, to firmly attach the blades to the rotor, and, when the blades are large and of relatively costly construction, it is also desirable to provide a mounting which will permit removal of the individual blades without damaging either the blades or the support. The present invention contemplates improvements in turbine blade mountings, whereby blades of various sizes may be firmly locked to a support, but which will permit convenient removal of the blades, and re-assembly of the structure, without damaging the parts. Other advantages attainable with the present improvement will appear from the accompanying detailed description.

A clear conception of the several steps of the improved method, and of the mode of constructing a bladed rotor in accordance with the invention, will be apparent from the accompanying drawings in which like reference characters designate the same or similar parts in the several views.

Fig. 1 is a top view of three normal blades, showing the same attached to a fragment of a supporting rotor.

Fig. 2 is a radial section through a fragment of a rotor having a fragment of a normal blade attached thereto.

Fig. 3 is a top view of two normal and an intermediate special blade, showing the normal blades attached to a fragment of a supporting rotor and also showing the special

blade in position preparatory to attachment thereof.

Fig. 4 is a radial section through a fragment of a rotor at the place of attachment of a special blade thereto, showing a fragment of a special blade in position preparatory to attachment thereof. 55

Fig. 5 is a top view of two normal and an intermediate special blade, showing the same during the process of attachment thereof to 60 a fragment of a rotor.

Fig. 6 is a radial section through a fragment of a rotor, similar to that of Fig. 4, showing a fragment of a special blade during the process of attachment thereof to the 65 rotor.

Fig. 7 is a view similar to that of Fig. 6, showing the special blade fastening further advanced during the process of attachment to the rotor. 70

Fig. 8 is a view similar to that of Figs. 6 and 7, showing the process of attachment of the special blade at a more complete stage.

Fig. 9 is a view similar to that of Figs. 6, 7 and 8, showing the special blade finally 75 locked to the fragment of the rotor.

Fig. 10 is a top view of two normal and an intermediate special blade, showing the blades finally locked to a fragment of a rotor.

Fig. 11 is a top view of two normal and an intermediate special blade, showing a modified form of final locking arrangement for the special blade. 80

Fig. 12 is a fragmentary side view of a rotor and blading, showing the mode of application of a special jig used for the purpose of fastening the special locking blade in position. 85

Fig. 13 is a fragmentary radial section through the rotor and through the jig of 90 Fig. 12.

In accordance with the improvement, the rotor or support 2 may be provided with one or more peripheral annular grooves 21, each of which has serrations 12 in the opposite side walls thereof, as shown in Figs. 1 and 2. Each of the grooves 21 is also provided with one or more local lateral recesses or enlargements 16 as shown in Figs. 3 and 4, of a size to permit insertion into the ad- 95 porting 100

adjacent grooves 21, of blade bases having transverse cross sections snugly fitting the groove. The lateral enlargement 16 extends away from the adjacent groove 21, a distance 5 slightly greater than the depth of the serrations 12 on the opposite side of the groove, so that the bases of normal blades 4 may be inserted into the groove 21 at the enlargement 16, and subsequently slid along the 10 groove to their final positions. After the normal blades 4 have been thus applied to fill the entire groove except the portions at the enlargements 16, each of these enlarged portions of the grooves 21 is filled as shown 15 in Figs. 3 and 4, with the base of a special blade 3, said base having one side formed to snugly fit the serrations 12 on the side of the groove opposite to the enlargement, and having its opposite side adjoining the enlargement 16 formed as a plane inclined surface.

When the groove 21 has been thus finally substantially filled with blade bases, the special blades 3 may be locked in position by 25 snugly inserting a filler block or core 19 within each of the enlargements 16. This core may either be fitted and subsequently driven into place, or it may consist of metal poured into the enlargement or space, while in molten 30 condition. In Figs. 5 and 6, the block 19 has been fitted and driven into space and has an enlarged upper portion 8. The block 19 snugly engages the base of the blade 3 along the plane side surface thereof, and 35 should likewise snugly fit the walls of the enlargement 16.

After the core 19 has been inserted, a jig 5 such as shown in Figs. 12 and 13 may be applied to the rotor. The jig 5 is provided with 40 positioning dowels 6 which are adapted to engage drilled holes in the rotor, and may be held firmly in position by means of a jig clamp 7 coacting directly with the jig 5 as shown. The clamp 7 is secured to the outer 45 end of a clamping rod 9, the inner end of which is screw threaded. An inner clamp 10 embraces the threaded end of the rod 9 and a nut 11 coacting with the screw threaded portion of the rod 9 serves to draw the clamps 7, 50 10 together and to thus firmly lock the jig 5 in place.

When the jig 5 has been thus properly rigidly positioned, holes may be drilled through the core 19 by utilizing the threaded holes 20 55 of the jig 5 as guides, or a special drilling jig may be used which is a duplicate of jig 5 except that the drill guiding holes are not threaded, the drill used being of diameter not greater than the internal diameters of the 60 threads of the holes 20. The holes 20 are properly directed to cause the drill to follow the metal of the core 19, and should be drilled to substantially the bottom of the adjacent groove 21. When these holes have been 65 drilled, a tap guided by the threaded open-

ings 20 and snugly fitting these openings, may be utilized to form screw threads in the drilled holes thus producing the tapped holes 1 shown in Fig. 7. The threads of the tapped holes 13 project beyond the core 19 into the portions of the support 2 and of the base of the blade 3 on opposite sides of the enlargement 16.

With the tapped holes 13 thus formed, retaining screws or plugs 14 may be inserted into the holes 13 by applying a wrench to the heads 15 of the plugs 14, thus firmly locking the special blades 3 in position as shown in Fig. 8. The screw plugs 14 should snugly fit the tapped holes 13 in order to eliminate looseness between the interconnected parts. When the plugs 14 have been driven home, the enlargement 8 of the core 19 together with the upper portions of the screw plugs 14 may be cut off as shown in Fig. 9. The projecting portions of the screw plugs 14 and the enlargement 8 of the core 19 may be removed flush with the outer surface of the rotor 2 as shown in Fig. 9, or the plugs 14 may be permitted to project slightly beyond this surface and be provided with transverse end slots in order to permit most convenient removal thereof with a screw driver. After the structure has been thus finished, a relatively small locking screw 17 such as shown in Fig. 10 may be inserted between the adjacent screw plugs 14, in order to avoid possibility of undesirable unscrewing of the plugs 14. This locking screw 17 may be dispensed with, in favor of another screw plug 18 driven in between the original plugs 14, as shown in Fig. 11, thereby substantially replacing the entire core 19 with screw plugs 14, 18. The screw threads of the plugs 14, 18, in every case, should coact with the rotor 2 and with the base of the blade 3, in order to eliminate any possibility of loosening of the blade 3.

If, however, it becomes desirable to remove the blading from a groove 21, the screw plugs 14, 18 may be readily removed either by forming a slot in the end of each plug and unscrewing the same with the use of a screw driver, or by utilizing the same jig 5 that was used in the formation of the threaded holes 13, for the purpose of drilling out the plugs 14, 18.

When it is desired to replace the special blades 3 with other such blades, the procedure of fastening is the same as when the original blades were secured to the rotor and the same 1 jig, or a duplicate of the original jig is used. This jig is held to the rotor in the same position as was done for the original installation by means of the dowels 6 and clamp 9 so that the threads being cut in the new core 19 and the new blade 3 will exactly match up with the original threads in the rotor.

From the foregoing description of the structure and of the apparatus utilized in producing the same, it will be apparent that 1

the blades 3, 4 may be firmly locked in position within the grooves 21 and cannot become displaced during normal operation of the machine. The blades may however be readily removed without marring either the support or the blade bases, and may be replaced by other blades. The attachment may be applied to blading for either a rotor or a stator, it obviously being possible to utilize a jig arrangement similar to that shown in Figs. 12 and 13, when applying a blade to a stator. In case the support 2 is of large diameter thereby making the groove 21 relatively long, several enlargements of each groove 16 may be utilized, thereby reducing the time required for assembling or dismantling of the structure. The small jig holes for receiving the positioning pins 6 do not have to be drilled deep and therefore are not objectionable in a rotor of this type, and these holes permit accurate positioning of the jig 5 when fastening, detaching or replacing the blading. The holes 20 of the jig 5 accurately guide the drills and taps and insure possibility of removing the screw plugs 14 without undesirably marring the support 2 and the base of the blades 3. The filler cores 19 facilitate proper drilling and tapping of the threaded holes 13 without danger of breaking the drills and taps, and the entire assemblage is not only rigid but presents a neat final appearance.

It should be understood that it is not desired to limit the invention to the exact details of construction and to the precise mode of attaching blades herein shown and described, for various modifications within the scope of the claims may occur to persons skilled in the art.

It is claimed and desired to secure by Letters Patent:

1. A turbine blade mounting comprising, a support having a groove provided with a local enlargement, a plurality of blades having adjoining bases substantially filling said groove, a core located within said enlargement and coacting with an adjacent blade base, and a locking plug embedded in said core and interlocking with said support and said blade base.

2. A turbine blade mounting comprising, a support having an annular groove provided with a local enlargement, a plurality of blades having adjoining bases interlocking with the sides of said groove, a core substantially filling said enlargement and coacting with an adjacent blade base, and a plug embedded in said core and having screw threads interlocking with said support and said blade base.

3. A turbine blade mounting comprising, a support having an annular groove provided with serrated side walls and with a local enlargement at one side thereof, a plurality of blades having bases provided with projections interlocking with said serrations, a core

removably disposed within said enlargement, and a plug for locking said core within said enlargement, said plug having screw threads interlocking with said support and said blade base adjoining said enlargement. 70

4. A turbine blade mounting comprising, a support having an annular groove provided with side serrations and with a local enlargement at one side thereof, blades having bases insertable in said groove only at said enlargement, said bases having projections cooperable with said serrations to retain said bases within said groove, and a screw plug insertable within said enlargement and having threads cooperable with said support and with the blade base adjoining said enlargement to lock said base in place. 75 80

In testimony whereof, the signature of the inventor is affixed hereto.
